UNITED STATES PATENT OFFICE

PETER M. RUDESYLE, OF HAWTHORNE, NEW JERSEY

HIGH-PRESSURE PUMP

Application filed January 29, 1927. Serial No. 164,484.

The present invention relates to pressure pumps of the hand operated type for use in the forced feeding of lubricants into the working parts of machinery, and relates more specifically to devices of this character commonly known as grease or oil guns.

The primary object of the invention being to provide a novel and efficient type of pressure operated pump particularly well adapted for use in forcibly feeding of lubricants to the moving parts of an automobile or other machinery, and especially to those bearings and joints intended to be lubricated by heavy oils and greases forcibly injected thereinto.

15 A further object of the invention resides in the provision of a hand operated pressure pump as set forth, embodying a reciprocating plunger having actuating means connected therewith for forcibly moving of the plunger step by step in one direction for ejecting of the lubricants from the pump, and an automatically acting keeper means for preventing counter or back movement of the plunger during operation of the actuating means.

25 A further object of the invention is to provide an improved type of hand operated pressure pump which may be used either in connection with the distributing of either light oils or heavy greases.

30 A still further object of the invention is to provide an improved device of this character embodying an operating lever so mounted as to permit of great pressure being applied to the plunger for ejecting of the lubricant, and which lever has its major portion extending longitudinally of the barrel of the pump, with means for locking the lever in a position closely adjacent and extending longitudinally to one side of the barrel for 40 the pump.

A still further object of the invention is to provide a novel pump of this type wherein the pressure actuating means may be readily rendered inoperable for forced feeding of the plunger, and allowing for the plunger to be reciprocated by hand as when filling the pump, or when it is not essential that the lubricant be ejected from the pump under considerable pressure.

45 50 Other objects and advantages of the inven-

tion will be apparent during the course of the following detailed description, taken in connection with the accompanying drawing forming a part of this specification and in which drawing:

Figure 1 is a view part in longitudinal section and part in side elevation of the improved pressure pump and showing the plunger carrying stem in a position to be operated upon by the actuating means for 55 forced movement of the plunger.

Figure 2 is a fragmentary sectional view of the upper end of the pump and showing the plunger stem in a reverse position from that as illustrated in Figure 1 for permitting 60 of free reciprocation of the plunger.

Figure 3 is a fragmentary side elevation of the upper portion of the pump and showing the operating lever swung laterally of the pump barrel for moving the plunger inwardly.

Figure 4 is a fragmentary elevation of the upper portion of the pump and taken at a right angle from that as illustrated in Figure 3.

Figure 5 is a transverse section on line 5—5 of Figure 1.

Figure 6 is a detail sectional view of the lock for the operating handle.

Figure 7 is a fragmentary sectional view 80 taken substantially along the line 7—7 of Figure 1.

Referring to the drawing in detail, and wherein similar reference characters designate corresponding parts throughout the several views, the letter A designates a barrel or chamber for the lubricant, provided at one end with a cap B and at its opposite end with a head C; D an ejecting means movable in the barrel A; E actuating means for operation of the ejecting means D; F stop means for the means D; and G a locking means for the actuating means E.

The barrel or chamber A and which is of tubular formation, is preferably provided at 95 its lower end with a knurled portion 10 and is externally threaded at each end for threaded reception of the cap B and head C.

The cap B, for threaded connection with the lower or discharge end of the barrel A, is 100

preferably provided with an internally threaded nipple 11 into which may be threaded a flexible metal hose for conveying of the lubricant to any desired point.

5 The head C and which is intended for threaded connection with the opposite end of the barrel A, is provided with a guide block 12 formed with a guide opening 13 which when the head is threaded upon the barrel A, extends co-axially with the axis of the barrel. Extending rearwardly from each side of the guide block 12, are substantially flat ears 14 which project past the circumferential surface of the barrel A and also 10 project upwardly above the upper face of the block 12. These laterally and upwardly projecting ears 14 serve as means for pivotal mounting of the actuating means E.

15 The ejecting means D embodies a plunger 20 or piston 15 which is preferably provided with double acting washers, and extending from the piston 15 is a cylindrical stem or rod 16 which projects through the round guide opening 13 in the head block 12. The 20 outer end of the stem 16 is preferably provided with a suitable handle 17 which may be employed for movement of the piston 15 and for permitting of the ready rotation of the ejecting means D. Provided longitudinally of the stem 16, is a series of ratchet teeth 18 which co-act with the actuating means E for forcibly moving of the piston 15 step by step toward the discharge cap B.

25 Referring now to the actuating means E for forced operation of the ejecting means D, the same embodies an operating lever 20 being pivotally mounted at its upper end between the ears 14 as by means of a suitable fulcrum or pivot pin 21 mounted in the ears 14 above the guide block 12 and outwardly of the circumferential face of the tubular barrel A. The upper end of the lever 20 is preferably provided with an inwardly offset portion or shoulder 22, and positioned upon 30 opposite sides of the upper end of the lever 20, are sheet metal head plates 23 having flanges 24 provided at their rear edges for overlying the outer surface of the lever, and wings 25 which clamp about the inner side 35 of the lever below the shoulder 22. Extending forwardly or inwardly from each head plate 23, are plate like arms 26 which extend at opposite sides of the stem 16. Each of the arms 26 is provided with guide ways 27 which preferably open at the forward end of the arms as illustrated in Figure 2.

40 The actuating means E further embodies a sliding ratchet 30 provided with a guideway 31 for slidably receiving the cylindrical stem 16. Pivotally carried by the ratchet 30, is a suitable spring pressed pawl 32 which has its gripping point normally urged toward the stem 16 for engaging in the toothed rack 18. This pawl 32 may be pivotally mounted upon the pivot pin 33. Projecting

45 from each flat side face 34 of the sliding ratchet 30, are trunnions 35 which are intended to engage in the guideways 27 of the plate like arms 26. As will be observed, the flat side faces 34 and plate like arms 26 50 will retain the sliding ratchet 30 against rotation upon the cylindrical stem 16 and thus retain the pawl 32 in a set position and to the opposite side of the stem 16 from that of the pivotal mounting 21 of the operating lever 75 70 75 80 85 90 95 100 105 110 115 120 125 130 135 140 145 150 155 160 165 170 175 180 185 190 195 200 51 for permitting of the entry of air during filling of the barrel A, or when moving of the piston 15 toward the head.

In use, and when desiring to fill the barrel 5 A with a suitable lubricant, the stem 16 is first rotated by means of the handle 17 to a position whereby the ratchet teeth 18 will not be engaged by either the pawl 32 or the V shaped keeper portion 38 of the stop F, and 10 in which position as illustrated in Figure 2, the stem 16 may be readily drawn thru the head C and sliding ratchet 30 for withdrawing of the piston 15. The cap B may then be removed and the barrel filled with a suitable 15 grease, and the cap then threaded upon the barrel and a flexible hose connected to the nipple 11 if such hose is to be used for conveying of the lubricant to inaccessible places. The stem 16 may then be rotated by means 20 of the handle 17 into a position as illustrated in Figure 1, and upon grasping the open handle 50 and swinging the lever 20 away from the barrel A about its pivot 21, the free ends of the arms 26 will force the sliding 25 ratchet 30 toward the head C, and by reason of the pawl 32 engaging in one of the ratchet teeth 18, the piston 15 will be moved toward the cap B for forcing of the lubricant through the nipple 11. As the sliding ratchet 30 moves for forward movement of the ejecting 30 means D, the ratchet teeth 18 readily move past the spring pressed keeper portion 38 until the sliding ratchet engages the guide block 12 which act as a stop for limiting 35 outward swinging movement of the operating lever 20. Upon returning of the lever 20, the stop F engages with the proper ratchet tooth and prevents counter or outward movement 40 of the ejecting means due to the pressure formed in the barrel A. If using light lubricants such as oil, the lever 20 may be locked against the barrel A by means of the locking 45 means G, and the ejecting means operated solely by means of the handle 17 with the ratchet teeth in a position as illustrated in 50 Figure 2. When using light oils in the pump, the same may merely be sucked through the nipple 11 without necessarily removing of the cap B.

55 Referring again to the piston 15, and which is of improved construction for enabling the piston to hold up under heavy pressure, the same embodies an inner washer of special formation, provided with a cup portion 60 and a disc portion 61 which is adapted to engage the inner cup washer 62. Arranged between the inner washer 62 and an outer washer 63, is a metallic disc 64 which is preferably of a diameter equal to the inner diameter of the 60 barrel A, and disposed outwardly of the washer 63, is a retaining washer 65 held in position by means of a nut 66 threaded upon the reduced threaded end 67 of the stem 16. As will be observed in Figure 1, this reduced 65 stem portion 67 provides a shoulder against

which the inner washer abuts, and by reason of the cup portion 60 of the washer snugly embracing the stem 16, the piston 15 is prevented from tilting when a considerable pressure is applied to the piston by means of the actuating means E.

70 From the foregoing description it will be apparent that an extremely simple and novel type of pressure operated pump has been provided, embodying a novel type of actuating means whereby the piston may be moved step by step in one direction for the force feeding of lubricants from the pump, and embodying automatically acting keeper means for preventing counter or back movement of the piston during operation of the actuating means. It will also be apparent that a novel construction has been provided for the actuating means whereby the lubricant may be ejected under great pressure from the pump and thus forced into tight bearings and joints for effective lubrication thereof. It will also be apparent that the actuating means embodies a relatively long operating lever 75 for securing of a good leverage for operation of the ejecting means, and which relatively long handle normally lies longitudinally to one side of the barrel for containing the lubricant.

80 Changes in detail may be made to the specific form of the invention herein shown and described, without departing from the spirit of the invention or the scope of the following claims.

85 I claim:

1. A pressure pump comprising a barrel provided at one end with a discharge opening, a head carried by the opposite end of the barrel provided with a guide opening and spaced apart ears projecting laterally from the head, a stem provided with ratchet teeth, movable in the guide opening and carrying a piston at its inner end, a ratchet member guided on the stem outwardly of the head and including a pawl engageable with the ratchet teeth of the stem to move the stem in unison with the ratchet member for forcing material thru the discharge opening of the barrel, an operating lever extending longitudinally at one side of the pump barrel and pivotally mounted between the laterally projecting ears of the head outwardly of the circumferential face of the barrel, and arms carried by the pivoted end of the lever, and extending inwardly at each side of said stem and having slotted ends 100 for slidable connection with said ratchet to reciprocate the latter by oscillation of the lever.

105 2. A pressure pump including a barrel provided at one end with a head having a guide opening and spaced apart ears projecting laterally of and above the head, a piston, a stem for the piston slidable and rotatable in said guide opening and having ratchet teeth extending longitudinally at one side thereof, a

- handle carried by the outer end of the stem, an actuating means for the stem including a ratchet slideable along the stem and a lever pivotally mounted between said ears and extending longitudinally of one side of the pump barrel, and locking means carried by one of said ears and engageable with said lever for locking the lever against pivotal swinging and in close proximity to one side of the pump barrel.
10. 3. In a pump of the class described, a cylinder, a head for one end of the cylinder provided with a guide opening, a piston stem provided with ratchet teeth, slideable in the guide opening, a ratchet member guided on said stem and including a pawl engageable with said ratchet teeth upon movement of the ratchet toward said head, and means for moving the ratchet toward and away from said head.
15. 4. In a pump of the class described, a cylinder, a head for one end of the cylinder provided with a guide opening, a piston stem provided with ratchet teeth, slideable and rotatable in the guide opening, a ratchet member slideably and non-rotatably guided on said stem and including a pawl engageable with said ratchet teeth for movement of the ratchet toward the head, operating means for imparting movement to the ratchet along the stem, and a cylindrical stop member rotatably carried by the head and having a keeper portion engageable in the ratchet teeth for preventing retroactive movement of the piston stem.
20. 5. In a high pressure pump including a pump barrel, a piston rod including a body portion having a reduced, threaded inner end forming a shoulder, and a piston for the rod comprising an inner washer member including a cup portion slideably fitting over the rod body portion and a disc portion engaging said shoulder, an inner cup washer in engagement with said disc portion, an outer cup washer facing oppositely from the inner cup washer, a metal disc between the cup washers, a retaining washer in engagement with the outer cup washer, and a retaining nut threaded upon the reduced end of the piston rod for clamping the piston elements to the piston rod.
25. 6. In a pressure pump including a barrel and a head at one end of the barrel, a cylindrical piston rod slideably and rotatably extending thru the head and having transversely disposed ratchet teeth extending in spaced relation longitudinally along one side thereof, a handle at the outer end of the rod, actuating means for imparting inward movement to the rod including a pawl operating at one side of the rod for engagement with the teeth thereof, and a stop, carried by the barrel head, operatively engageable with the said teeth of the piston rod when the rod is in operative relation to said pawl.
